(57) **CLAIM**

The ornamental design for a microwave cooker, as shown and described.

DESCRIPTION

FIG. 1 is a perspective view of a microwave cooker, showing my new design in a combined state;

FIG. 2 is another perspective view thereof;
FIG. 3 is a front elevational view thereof;
FIG. 4 is a rear elevational view thereof;
FIG. 5 is a left elevational view thereof, the right side view being a mirror image of FIG. 5;
FIG. 6 is a top side view thereof;
FIG. 7 is a bottom plan view thereof;
FIG. 8 is a partial enlarged view of FIG. 1;
FIG. 9 is a partial enlarged view of FIG. 1;
FIG. 10 is a perspective view of the microwave cooker in a disassembled state;
FIG. 11 is a perspective view of the first piece of the microwave cooker, in different angles;
FIG. 12 is another perspective view thereof;
FIG. 13 is a front elevational view thereof;
FIG. 14 is a rear elevational view thereof;
FIG. 15 is a left elevational view thereof, the right side view is identical;
FIG. 16 is a top side view thereof;
FIG. 17 is a bottom plan view thereof;
FIG. 18 is a perspective view of the second piece of the microwave cooker, in different angles;
FIG. 19 is the second perspective view thereof;
FIG. 20 is the third perspective view thereof;
FIG. 21 is the fourth perspective view thereof;
FIG. 22 is a front elevational view thereof, the rear elevational view is identical;
FIG. 23 is a left elevational view thereof, the right side view being a mirror image of FIG. 23;
FIG. 24 is a top side view thereof;
FIG. 25 is a bottom plan view thereof;
FIG. 26 is a perspective view of the third piece of the microwave cooker, in different angles;
FIG. 27 is another perspective view thereof;
FIG. 28 is a front elevational view thereof, the rear elevational view is identical;
FIG. 29 is a left elevational view thereof, the right side view being a mirror image of FIG. 29;
FIG. 30 is a top side view thereof; and,
FIG. 31 is a bottom plan view thereof.
The broken lines in the figures are for the purposes of illustrating portions of the microwave cooker, which form no part of the claimed design.
